CLAIM

The ornamental design for a packaging, as shown and described.

DESCRIPTION

FIG. 1 is a top front perspective view of a packaging, showing our new design;

FIG. 2 is a front elevation view thereof;

FIG. 3 is a rear elevation view thereof;

FIG. 4 is a right-side elevation view thereof, the left-side elevation view being a mirror image thereof;

FIG. 5 is a top plan view thereof; and,

FIG. 6 is a bottom plan view thereof.

The broken lines in the figures illustrate the portions of the packaging and form no part of the claimed design.
